UNITED STATES PATENT OFFICE.

ALBERT ANDERSEN AND WILLIAM A. CHAPIN, OF CHICAGO, ILLINOIS, ASSIGNOR TO AUTOMATIC ELECTRIC COMPANY, OF CHICAGO, ILLINOIS, A CORPORATION OF ILLINOIS.

AUTOMATIC TELEPHONE SYSTEM.

Application filed December 23, 1920. Serial No. 432,818.

To all whom it may concern:

Be it known that we, ALBERT ANDERSEN and WILLIAM A. CHAPIN, both citizens of the United States of America, and residents 5 of Chicago, Cook County, Illinois, have invented certain new and useful Improvements in Automatic Telephone Systems, of which the following is a specification.

The present invention relates in general 10 to automatic telephone systems, but is more particularly concerned with small systems such as are commonly known as private automatic exchanges. Systems of this character have come into extended use in department stores, manufacturing plants, and the like. It is well understood that in an installation of this kind the more exacting requirements of the subscribers render it necessary to provide a number of features 15 which are not needed in a public exchange. The present invention is concerned particularly with one of these features, a feature that is known as conference calling. This is an arrangement to enable an official of a 20 company having a private automatic exchange, or P. A. X., to communicate with a number of his employees at the same time instead of having to talk to each one individually. That is, a conference connection 25 may be established which includes three or more telephone sets all connected to the same conversational circuit at the same time.

Figs. 1 and 2, when arranged with Fig. 2 underneath Fig. 1, show the invention.

Fig. 1 shows the usual type of automatic telephone substation A having a line switch C of the well known plunger type individual thereto. This line switch in common with the line switches C', C'', and a plurality of 30 similar line switches in the group are adapted to be controlled by a master switch D and have access to trunk lines leading to connector selector repeaters similar to those shown at H and H'. The function of the 35 master switch D, as is well known, is to maintain all idle line switches opposite an idle trunk line. The connector selector repeaters H and H' are of the well known Srowger vertical and rotary type and have 40 the usual 100 contact sets arranged in ten rows or levels. The first eight levels are arranged for local traffic within the branch exchange and when working on these levels

the switch H and similar switches have the function of ordinary connectors except on 55 the conference number. This exception will be explained fully hereinafter. The two top levels, namely, the ninth and tenth, are reserved for trunk lines. On these levels 60 the switch H has the function of an ordinary selector. That is, when raised to the ninth or tenth level the switch will operate automatically to select an idle trunk line. The trunk lines terminating in one level, say the tenth, extend to another P. A. X. 65 and on this level the switch H has also the function of an automatic impulse repeater.

The arrangement of the different bank 70 levels may be better understood in the more detailed consideration of the situation in which the P. A. X. is used. It is assumed that the concern using the P. A. X. has two factories or other establishments located a short distance apart in a city served by a 75 public manual exchange. One of the factories is supplied with telephone service by the P. A. X. under discussion while the other factory is supplied with telephone service by another private automatic exchange of the same type. The tenth level of the selector connector repeaters in the P. A. X. at factory number 1 is reserved for private trunk lines extending to the P. A. X. at factory No. 2, while the ninth level is used for trunk lines extending to a public 80 manual exchange.

From this explanation the wiring of the banks of the switches H and H' will be readily understood. The conductors terminating in the bank contacts 130-132, inclusive, 90 lead to a local substation B, which is similar to the one shown at A, and are of course multiplied into the several connector switches. The bank contacts 138-140, inclusive, are the terminals of a trunk line extending to the P. A. X. in factory No. 2, 95 and are multiplied into the local connector switches and represented in the connector H' by the contacts 280-282, inclusive. The contacts 141-143, inclusive, are the terminals of a trunk line leading to the public manual exchange and are multiplied in the usual manner throughout the local connectors, the contacts 283-285, inclusive, being the multiple into the switch H'. The multiples between these contacts in the ninth 100

and tenth level are not shown for the reason that their inclusion would unduly complicate the drawings. Bank contacts 125-127, inclusive, are contacts assigned to the conference number which it will be assumed is the number 60. There is also a multiple between these contacts into the various switches but the conductors leading from these and similar bank contacts in the switches are taken through the break springs of a relay, one of a group of two associated with each connector, before being joined to the multiple. These relays associated with the switch H are characterized in the drawings by the reference numerals 150 and 151 and relays 260 and 261 are associated with the switch H'. The multiple conductors of the conference number terminate in a plunger type line switch C' which has access to the local connectors including the connectors H and H'.

Having briefly described the apparatus in the system, a more detailed description of its operation will now be given. For this purpose it will be assumed that the subscriber at substation A desires to have a conference with a number of other subscribers. To do this he will call the regular local number of the first subscriber desired in the conference prefixing the conference number (60). When the receiver is removed at substation A a circuit is closed for the energization of the slow acting line relay 15 of the individual line switch C over the following path: ground G', springs 35, line conductor 12, through the substation A, line conductor 11, springs 34, and thence through the winding of the line relay 15 to battery. The line relay 15 is energized over the above circuit and upon attracting its armature 18 completes a circuit for the pull down winding 16. The pull down winding, upon energizing, attracts the plunger arm 25 and the cut off armature 26; the former by means of its plunger forcing the springs 37-40, inclusive, into engagement with their resting contacts, and the latter disconnecting the line conductors 11 and 12 from ground and battery respectively, by separating the contact springs 35 and 34. By the engagement of springs 37 and 40 with their resting contacts line conductors 11 and 12 are extended to the double wound line relay 60 at the connector H which, upon energizing, completes the circuit of the slow acting release relay 61. Upon operating, the relay 61 at armature 81 places ground on the release trunk conductor extending back through working contact of spring 38 and the said spring and then through the holding winding 17 of the line switch C to battery. The holding winding 17 is thereby energized in order to maintain the cut off armature 26 and the plunger arm 25 in an operated position. This holding circuit is established be-

fore the slow acting line relay has had time to fall back. In addition to the function explained, the holding circuit also serves to maintain ground potential on the private normal conductor 30 which extends to the multiply connected test contacts in the banks of connector switches which have access to the line on which the subscriber at substation A is located, thus guarding the line against intrusion in the ordinary manner. Another circuit closed by the operation of the line switch C is completed by the engagement of bank spring 39 with its resting contact. When these contacts are closed ground is extended in an obvious manner to the test contact associated with the selected trunk line in the test bank of the master switch D whereby the said master switch is operated and the plungers of all the other idle line switches in the group are advanced into association with an idle trunk line.

The foregoing operations have occurred in response to the removal of the receiver at substation A and the line of the subscriber thereat has been extended by means of the line switch C into connection with an idle connector switch which is shown at H. The calling subscriber may now operate his calling device in accordance with the digits assigned in the conference number which, as before mentioned, is the number 60. When the calling device is operated for the first digit 6, six interruptions are produced in the circuit of the line relay 60 which de-energizes a corresponding number of times in response thereto. At each retraction of its armature 80 a circuit is completed extending from ground G', armature 80 and its back contact, armature 82 and the front contact, off normal springs 83 and 84, winding of the slow acting series relay 62, and the winding of the vertical magnet 71 to battery. The above is the circuit over which the first impulse is transmitted. At the first upward movement of the shaft the off normal springs are shifted and the circuit is completed over a new path which is the same as the one previously traced except that it includes the off normal springs 83 and 85 and armature 87 of the series relay 62 and its front contact, (the series relay being now in operated position). By the operation of the vertical magnet 71 the wipers 120-122, inclusive, are raised step by step until they stand opposite the sixth level of bank contacts in which is located the set of contacts associated with the conference number 60. The slow acting series relay 62, which is energized in series with the vertical magnet, maintains its armature attracted throughout the vertical operation of the switch and at the end of the vertical movement deenergizes and transfers the operating circuit to the rotary magnet 72.

The calling subscriber may now operate

his calling device in accordance with the second digit of the conference number. As before a series of interruptions is produced in the circuit of the line relay 60 which energizes in response thereto a corresponding number of times. At each retraction of its armature 80 a circuit is completed for the rotary magnet 72 extending over the following path: ground G², armature 80 and its back contact, armature 82 and its front contact, off normal springs 83 and 85, armature 87 and its back contact, normally closed springs controlled by relay 67, armature 114 and its back contact, and thence through the winding of the rotary magnet 72 to battery. The slow acting relay 68 is also energized in multiple with the above traced circuit thereby connecting the test wiper 121 to the test relay 67. The magnet 72 operates to rotate the wipers 120-122, inclusive, into engagement with the set of contacts associated with the conference number. Springs 94 and 77 are adjusted to be shifted into engagement with their working contacts 95 and 78 by a rotary cam on the switch when the switch shaft is rotated onto the conference number and then only. A circuit is completed by the engagement of springs 94 and 95 extending from ground G⁴, through the winding of relay 65, springs 94 and 95, and then through the lower winding of the ring cut off relay 66 to battery. Relays 65 and 66 energize over this circuit, relay 66 establishes a locking circuit for itself at armature 97 and at armature 96 and 98 and their front contacts prepares a repeating circuit. Upon the de-energization of slow acting relay 68 a circuit may be traced from ground on release trunk conductor 98', armature 100 and its back contact, through the lower winding of the switching relay 69, back contact and armature 106, normally closed contact springs controlled by the relay 69, test wiper 121, test contact 126, and thence through the winding of relay 151 to battery. Relays 151 and 69 operate over this circuit. Relay 69 establishes a locking circuit for itself at armature 112 and its front contact, opens the rotary magnet circuit at armature 114 and completes the operating circuit for the line relay 175 of the line switch C'.

The conductor leading from each test contact of the conference number in the several connector switches terminates in a relay associated with each connector, the conductor leading from the test contact 126 terminating in the relay 151 associated with the connector H. It follows therefore, that even though relay 69 operates to place ground on the test contact 126 this will not extend to the test contacts in any of the other switches. This however, will have no harmful effect for the reason that only one per-

son, probably the manager, will have the privilege of setting up a conference and hence only one conference can possibly be going on at the same time.

To proceed, relay 175 energizes over a circuit extending as follows: ground G²⁰, springs 179, conductor 166, conductor 172, back contact and armature 153, bank contact 127, wiper 122, front contact and armature 115, armature 98, and its front contact, front contact and armature 83', and through the lower winding of the impedance coil 64, armature 93 and its front contact, front contact and armature 92, upper winding of the impedance coil 64, back contact and armature 105, front contact and armature 96, armature 111 and its front contact, wiper 120, bank contact 125, armature 152 and its back contact, conductor 170, conductor 165, springs 178, and through the winding of the line relay 175 to battery. Upon energizing, relay 175 completes a circuit for pull down winding 176. The pull down winding 176, upon energizing, attracts the plunger arm 189, and the cut off armature 180. By the operation of the plunger arm the springs 185-198, inclusive, are forced into engagement with their working contacts and the line conductors 165 and 166 are extended to the line relay 190 of the connector H' by the shifting of springs 185 and 188 into engagement with their working contacts. Relay 190, upon energizing, completes a circuit of the slow acting release relay 191 which operates to establish a holding circuit by placing ground on the release trunk conductor 200 extending by way of working contact of spring 186 and the said spring through the holding winding 177 of the line switch C' to battery. This ground also extends over conductor 163 to the winding of the slow acting relay 155 to battery which energizes and prepares a circuit for the relay 156. The relay 156 does not energize at this time being short circuited by the holding ground on conductor 163. Relays 155 and 156 are of high resistance while the resistance R² is of low resistance, therefore relay 155 upon operating does not establish a locking circuit for itself at armature 176.

The subscriber at substation A may now operate his calling device in accordance with the first digit of the local subscriber's number thereby producing a series of interruptions on the line circuit of relay 60. At each deenergization of relay 60 the bridge across the trunk conductors is opened at armature 83'. A corresponding series of impulses is thereby produced in the circuit of the line relay 190. Slow acting relay 68 is energized also by the operation of relay 60 and serves to remove the impedance coil 64 from across the trunk conductors while the dial impulses are being sent. The line relay 190

of the connector H' operates in the usual manner to send a series of impulses to the vertical magnet 206 in series with the slow acting relay 192. The vertical magnet 206 5 operates to raise the wipers 250-252, inclusive, opposite the level of bank contacts in which the desired subscriber's line is located. When the subscriber at substation A operates his calling device for the next digit 10 of his desired number relay 60 responds to the interruptions in its line circuit and repeats them to the line relay 190 of the connector H'. Relay 190 at each retraction of its armature sends an impulse of current to 15 the rotary magnet 207 in multiple with the slow acting relay 198. The magnet 207 operates to rotate the wipers 250-252, inclusive, into engagement with the set of contacts with which the desired called subscriber's line is associated, which it will be 20 assumed, is the set of contacts 289-291, inclusive, associated with the line of subscriber at substation B. Relay 198 operates to connect the test wiper 251 to the test relay 197. If the desired subscriber's line be 25 busy at this time ground potential will be present on test contact 290 engaged by the test wiper 251. A circuit may then be traced extending from the said grounded test contact by way of test wiper 251, normally closed springs controlled by relay 199, armature 215 and its front contact, armature 239 and its back contact, and thence through the winding of the test relay 197 to battery. 30 Upon energizing, relay 197 completes a locking circuit for itself at armature 216 and places the busy tone on the calling subscriber's line over a circuit extending from the busy machine T' by way of armature 218 35 and its front contact, normally closed contact springs controlled by relay 198, bank contact engaged by the spring 188 and the said spring, conductor 166, conductor 172, back contact and armature 153, bank contact 40 127, wiper 122, front contact and armature 115, armature 98 and its front contact, front contact and armature 83 from whence it flows over the line conductor 12 to the substation A. This tone will notify the subscriber 45 that for the time being his desired number is busy, and he will replace his receiver upon the switchhook initiating the release of the switches C, H and H' in the usual manner. 50 However, it will be assumed in the present case that the desired subscriber's line was idle when connection thereto was attempted. Under these circumstances following the de- 55 energization of the slow acting relay 198 a circuit is completed extending from ground on the release trunk conductor 200, armature 216 and its back contact, through the lower winding of the switching relay 199, back contact and armature 215, nor- 60 mally closed springs controlled by relay 199, test wiper 251, test contact 290, conductor 168 and thence through the holding winding 300 of the line switch C' to battery. The holding winding 300, as is well known, is only strong enough to attract the cut off 70 armature 301 thereby removing the line conductors of the called substation from their normal battery and ground connections. Relay 199, upon operating, establishes a locking circuit for itself at armature 225 75 and its front contact, opens the rotary magnet circuit at armature 226, and prepares the ringing circuit of the called subscriber at substation B which is now effective extending from the ungrounded pole of generator by way of back contact and armature 222, armature 229 and its front contact, wiper 252, bank contact 291, conductor 169, over the line conductor, through the ringer and condenser of the substation B, line conductor, conductor 167, bank contact 289, wiper 250, front contact and armature 227, armature 221 and its back contact, and thence through the lower winding of the ring cut off relay 196 to battery. Relay 196 80 is so adjusted that it does not respond to alternating current and hence the ringing of the subscriber at substation B will continue intermittently until an answer is obtained. When this occurs a circuit for direct current will be completed over the above traced ringing circuit through the ring cut off relay 196. Relay 196 energizes and completes a locking circuit for itself at armature 85 220 and at armatures 221 and 222 opens the previously traced ringing circuit and at their front contacts completes a circuit for the back bridge relay 194. Relay 194, upon energizing, completes a circuit for the slow acting relay 193 at its armature 223. The calling subscriber at substation A may converse 90 with the subscriber at substation B and inform him that a conference is to be held and the numbers of the subscribers desired 95 in the conference, after which the subscriber at substation B will hang up his receiver thereby breaking the circuit of the back bridge relay 194. Upon the deenergization of relay 194 ground is removed for a short 100 interval from the release trunk conductor 110 200 that is, during the interval that the slow acting relay 193 remains operated after the deenergization of relay 194. This operation breaks the circuit of the holding winding 115 177 of the line switch C', also the circuit of the slow acting relay 155 and at the same time removes the short circuit around relay 156. The slow acting relay 156 energizes 120 and prepares a circuit which is effective upon the energization of the line relay 175. When the holding winding deenergizes plunger arm 189 and cut off armature 180 resume the normal position. A circuit is 125 thereupon completed for the line relay 175 which again energizes closing the circuit 130

of the pull down winding 176 and also placing ground on conductor 164 extending by way of armature 159 and its front contact, conductor 171, normally closed springs controlled by relay 150, armature 157 and its front contact, and through the winding of relay 150 to battery. Relay 150 energizes thereby establishing a locking circuit for itself at armature 156 and at armatures 152 and 153, opening the circuit to the line switch C' and at the front contacts of these armatures extending the line conductors of the substation A to the conference holding trunk comprising conductors 173 and 174. The line switch C' and the connector H' will therefore release freeing the line of the subscriber at substation B.

The subscriber at substation B will now call the number of the next subscriber desired in the conference. When the receiver is removed at substation B the line switch C² will operate to extend the line of that subscriber to an idle connector switch in a manner hereinbefore explained. When this occurs the line relay of the connector switch so seized will energize completing the circuit of the slow acting release relay which also energizes and establishes a holding circuit for the line switch C². The subscriber at substation B will now operate his calling device in accordance with the digits of the conference number. The connector under his control is thereby stepped into engagement with the set of back contacts corresponding to 60. When this occurs the line switch C' associated with the conference number will operate as before to connect with an idle connector which it will be assumed is the connector shown at H'. The subscriber at substation B will thereupon operate his calling device in accordance with the local number of the subscriber next desired in the conference. The connector H' will therefore be operated into engagement with the set of bank contacts associated with the line of the desired subscriber. If this line is busy a busy signal will be given to the calling subscriber at substation B in the usual manner. However, it will be assumed in the present case that the line of this subscriber is idle when connection thereto is attempted. The connector H will now operate to intermittently supply ringing current to the line of the called subscriber until an answer is obtained. When this occurs the ring cut off relay 196 will energize and complete the circuit of the back bridge relay 194, which also energizes over the line circuit of the called subscriber. Upon energizing, relay 194 completes the circuit of the slow acting relay 193. Conversation may now be carried on between the subscriber at substation B and the second called subscriber. The calling subscriber will inform him that a conference is to be held and also

the numbers of the parties desired. When this last called subscriber hangs up his receiver ground is removed from the release trunk 200 in a manner hereinbefore explained and the relay similar to relay 150 associated with the connector used by the subscriber at substation B is operated to transfer the subscriber thereat onto the conference holding trunk.

In the same manner the second called party will call another subscriber and in turn be transferred onto the holding trunk. The last subscriber to be included in the conference will have to call a special number as he will not have another subscriber to call. This number is represented by the bank contacts 135-137, inclusive, associated with the connector H and is of course multiplied throughout the local switches in the usual manner. The last subscriber to be called will therefore operate his calling device in accordance with the number associated with the bank contacts 135-137, inclusive. When the receiver is removed the line switch individual to this subscriber's line operates to connect with an idle connector. This connector will be operated under the control of its line relay to connect with the bank contacts similar to contacts 135-137, inclusive. The line conductors leading from these contacts terminate directly in the holding trunk. Battery is placed through resistance on the private normal conductor 175'. The test wiper similar to the test wiper 121 of the connector H upon finding battery will complete and the circuit of the switching relay similar to relay 69. This relay will then operate to prepare the talking circuit. No ringing current will be applied to the holding trunk by this connector as the ring cut off relay of the connector is immediately operated, a path for direct current being effective through the impedance coil 64 and similar coils of the operated switches. All the subscribers desired in the conference are now connected with the holding trunk and each is supplied talking battery by the line relay of the various associated switches.

When the conference is terminated each subscriber by replacing his receiver upon the switchhook will open the circuit of the line relay of his associated connector switch thereby completing the release magnet circuit of each connector in the ordinary manner.

The explanation of the manner in which a trunk connection to the main exchange is established may now be proceeded with. As before stated, the trunk lines extending to the main exchange terminate in the ninth level. It follows therefore, that in order to connect with one of these trunk lines the digit 9 must be called. The subscriber at substation A who desires to connect with the 130

main exchange will therefore remove his receiver and operate his calling device in accordance with the digit 9. When the receiver is removed the line switch C operates as before described to extend the associated line to a trunk line terminating in an idle selector connector repeater. It will be assumed that the switch H is idle and is selected for use, when connection is extended thereto the line and release relays 60 and 61 are energized as previously explained and with the same results. When the calling device is operated the switch wipers 120-122, inclusive, are raised step by step by the vertical magnet 71 under the control of the line relay 60 and are brought to rest opposite the ninth level, all in the manner previously explained. When the wipers are raised to the ninth level the shaft controlled spring 74 is brought into engagement with spring 73 by the operation of the shaft. This may be accomplished by any suitable cam arrangement. A convenient way is to mount the spring assembly comprising springs 73-76, inclusive, just above the top of the shaft so that the springs 74 and 76 will be actuated by the circular cup spring casing which is mounted on the upper extremity of the switch shaft. To proceed, the slow acting relay 62 is energized in series with the vertical magnet and at armature 86 and its front contact completes a circuit extending from ground on release trunk conductor 98 by way of the shaft controlled springs 73 and 74, springs 78', armature 86 and its front contact, armature 77 and its back contact, and through the winding of the test relay 67 to battery. Upon energizing, relay 67 completes a locking circuit for itself at armature 100 and its front contact, and at armature 101 and its front contact prepares the rotary magnet circuit. Upon the termination of the vertical movement of the switch the slow acting relay 62 deenergizes and a circuit is thereby completed extending from ground on release trunk conductor 98 by way of the shaft controlled springs 73 and 74, springs 78, armature 86 and its back contact, armature 101 and its front contact, armature 114 and its back contact, and thence through the winding of the rotary magnet 72 to battery. Upon operating, magnet 72 steps the wipers 120-122, inclusive, into engagement with the first set of contacts in the ninth level and also breaks the locking circuit of the test relay 67 which deenergizes opening the circuit of the rotary magnet 72 which deenergizes also. In multiple with the above traced circuit for the rotary magnet a circuit is also completed for the slow acting relay 68 which operates to connect the test wiper 121 to the test relay 67. The further operation of the switch depends upon whether the trunk line associated with the bank contacts engaged by the wipers 120-122, inclusive, is or is not busy. If busy, a ground potential will be present on the test contact engaged by test wiper 121. A circuit is thereby completed extending from the said grounded test contact by way of the test wiper 121, normally closed springs controlled by the relay 69, armature 106 and its front contact, armature 77 and its back contact, and through the winding of the test relay 67 to battery. Relay 67 again operates to close the rotary magnet circuit at armature 101 and establish a locking circuit for itself at armature 100. Magnet 72 operates to rotate the switch wipers into engagement with the next set of contacts in the ninth level and break the locking circuit of relay 67. The alternate operation of relay 67 and magnet 72 will continue until an idle trunk line is found, which it will be assumed, is the trunk line terminating in the bank contacts 141-143, inclusive, the test contact 142 of which will be ungrounded. Ground being no longer present on the test contact engaged by the wiper 121 no circuit will be completed for the test relay 67. Following the deenergization of the slow acting relay 68 a circuit is completed extending from ground on release trunk conductor 98, by way of armature 100 and its back contact, through the lower winding of the switching relay 69, back contact and armature 106, normally closed springs controlled by relay 69, test contact 142, resistance R², to battery. Relay 69 energizes over this circuit establishing a locking circuit for itself at armature 112 and at armatures 111 and 116 and their front contacts prepares a ringing circuit. Ringing current is automatically projected over the trunk line which terminates in bank contacts 141-143, inclusive, in the same manner as in the case of a called local line and the ring down drop or other signalling device at the manual switchboard is operated in the usual manner. When the operator plugs in to an answer the call the ring cut off relay 66 is operated, disconnects the ringing current, and completes the talking connection. The connection to the desired local substation in the main exchange may be completed by the operator through the medium of any suitable means which need not be explained herein.

The operation of the selector connector repeater H when used for trunking to the second private automatic exchange is the same as in the case just described in so far as the selection of an idle trunk line is concerned, but since the connection in the private automatic exchange must be completed automatically the circuits of the switch H are altered suitably in order to permit the switch to operate as a repeater for the purpose of repeating impulses over the selected trunk line. Since the trunk lines leading to the second private automatic exchange ter-

minate in the tenth level the subscriber at substation A who desires to connect thereto will remove his receiver and operate his calling device for the digit 0. When the receiver is removed the line switch C operates as before to connect with an idle selector connector repeater II. When the digit 0 is sent to the switch the line relay 60 operates in response thereto and controls the vertical movement of the switch in stepping to the tenth level. On the tenth vertical step of the shaft the shaft controlled springs 73 and 74, and 75 and 76, are brought into engagement. The switch H will operate as previously described to select an idle trunk line leading to the P. A. X. number 2, where it terminates in a line switch or incoming connector similar to the connector H. This trunk line it will be assumed, is the trunk line terminating in bank contacts 138-140, inclusive. By the engagement of shaft controlled springs 75 and 76 the circuits of the switch H are altered in the same manner as when the cam springs 94 and 95 were brought into engagement when the conference number was called. The repeating circuit is thereby completed in the same manner as there described. The connection in the second private automatic exchange will therefore be completed in the usual manner.

Having fully ascertained and described the features of our invention, what we consider to be new and desire to have protected by Letters Patent will be pointed out in the appended claims.

What I claim as my invention is:

1. In a telephone system, calling and called lines, an automatic connector switch, means whereby the subscriber on one of said calling lines may establish a connection with one of said called lines by means of said switch, a holding trunk, and means responsive to the restoration of the receiver at the called substation for transferring the connection of the calling line to the said holding trunk.

2. In a telephone system, calling and called lines, automatic switches, means whereby the subscriber on one of said calling lines may establish a connection with one of said called lines through a series of said automatic switches, a holding trunk, and means responsive to the restoration of the receiver at the called substation for releasing a part of said series of switches and transferring the calling line into connection with the said holding trunk.

3. In a telephone system, calling and called lines, automatic switches, means whereby the subscriber on one of said calling lines may establish a connection with one of said called lines through a series of said automatic switches, a holding trunk, and means responsive to the restoration of the receiver at the

called substation for transferring the calling line into connection with the said holding trunk.

4. In a telephone system, calling and called lines, an automatic connector switch, means whereby the subscriber on one of said calling lines may establish a talking connection with one of said called lines by way of the said automatic switch, means under the control of the said calling subscriber only for releasing said automatic switch, means whereby the said calling subscriber may establish a connection with another of said called lines by way of the said automatic switch, and means under the control of the second called subscriber for releasing said automatic switch.

5. In a telephone system, calling and called lines, an automatic connector switch, means whereby the subscriber on one of said calling lines may establish a connection with one of said called lines by way of the said automatic switch, means under the control of the said calling subscriber only for releasing said automatic switch, means whereby the said calling subscriber may establish a connection with another of said called lines by way of the said automatic switch, and means under the control of either the calling or the second called subscriber for releasing said automatic switch.

6. In a telephone system, calling and called lines, automatic switches, a holding trunk, means whereby the subscriber on one of said calling lines may establish a connection with one of said called lines through a series of said automatic switches, means whereby the subscriber on said called line may place the calling line into connection with the holding trunk and then call a second called line, and means under the control of the subscriber on the second called line for placing the first called line into connection with the said holding trunk.

7. In a telephone system, calling and called lines, a holding trunk, automatic switches, means whereby the subscriber on a calling line may establish a connection with a called line through a series of automatic switches, means whereby the subscriber on the said called line may pass the connection to another called line, and means under the control of each called subscriber for placing the calling lines into connection with the said holding trunk.

8. In a telephone system, calling and called lines, an automatic switch, a second automatic switch accessible through the banks of said first switch, multiple bank contacts in each of said switches individual to said called line, means whereby the subscriber on the calling line can operate said first switch to connect with the called line independent of said second switch, and whereby the said subscriber can establish

another connection with the called line by operating said switches successively.

9. In a telephone system, calling and called lines, an automatic switch, a second automatic switch, bank contacts in said first switch individual to said called line, a second set of bank contacts in said first switch individual to said second switch, a third set of bank contacts in said second switch individual to said called line, means including the first switch for connecting said lines by way of said first set of bank contacts and independent of the other sets, and means including both switches for connecting said lines by way of the second and third sets of bank contacts.

10. In a telephone system, line switches individual to the subscribers' lines, connectors accessible to said line switches and having access to the subscribers' lines, a special line switch having access to said connectors in common with the subscribers' line switches, and a trunk line accessible to said connectors and terminating in said special line switch.

11. In a telephone system, line switches individual to the subscribers' lines, connectors accessible to said line switches and having access to the subscribers' lines, a special line switch having access to said connectors in common with the subscribers' line switches, a trunk line accessible to said connectors and terminating in said special line switch, sets of normal conductors constituting the means by which the connectors are

given access to said trunk line, another 40 trunk line, and a relay associated with each set of normal conductors for switching such conductors from said first trunk line to said second trunk line.

12. In a telephone system, a plurality of 45 connectors operable successively by different calling subscribers to establish connections with called lines, the subscriber on the called line in each connection being the calling subscriber who establishes the next connection, a common talking circuit, and means for switching each calling line into connection with said talking circuit when the subscriber on the associated called line hangs up preparatory to calling the next line. 55

13. In a telephone system, the method of establishing a conference connection which consists in having each subscriber except the last call the next subscriber, and in having each calling subscriber switched to a 60 common talking circuit by the subscriber he has called.

14. In a telephone system, the method of establishing a conference connection which consists in the establishment of a plurality 65 of separate connections by a plurality of successively calling subscribers, and in successively switching each calling subscriber's line on to a common talking circuit.

Signed by us at Chicago, Cook County, Illinois, this 10th day of December, 1920.

ALBERT ANDERSEN.
